Primary Examiner — Catherine Tuttle(74) *Attorney, Agent, or Firm* — Andrew P. Lahser**CLAIM**

The ornamental design for a baseball target, as shown and described.

DESCRIPTION

FIG. 1 shows a perspective view of my new design for a baseball target hanging on a fence.

FIG. 2 shows a front view thereof.

FIG. 3 shows a top view thereof, the appearance of the omitted bottom view being apparent from the views shown.

FIG. 4 shows a right side view thereof, it being understood that the opposite view is a mirror image; and,

FIG. 5 shows a rear view thereof.

In the drawings, the broken lines showing the fence in FIG. 1 indicate environmental subject matter and form no part of the claimed design.
